42. A wheel which contains the balance of the stand.

43. A wheel which contains the balance of the stand.

44. A wheel which contains the balance of the stand.

45. A wheel which contains the balance of the stand.

State of Massachusetts
County of Suffolk, ss.

On this second day of October in 1841, personally appeared before me, Richard Orman of Boston, in the state of Massachusetts, and made solemn oath that he is interested, as an assignee, in a Planing Machine, for which Letters Patent of the United States were granted to William Woodworth, on the twenty seventh day of December, A.D. 1828, and that the accompanying drawings are, as he verily believes, a true delineation of the invention described in the said Letters Patent.

R. H. Eddy, Justice of Peace.

Filed Office
Received by P. Perkins & Son
the 29th of Oct 1841
in the office of the Clerk of the Court of Common Pleas.
